UNITED STATES PATENT OFFICE.

PETER THOMSEN, OF CASSEL-WILHELMSHÖHE, GERMANY, ASSIGNOR TO SCHMIDT'SCHE HEISSDAMPF GESELLSCHAFT M. B. H., OF CASSEL-WILHELMSHÖHE, GERMANY, A CORPORATION OF GERMANY.

CONNECTING MEMBER FOR SUPERHEATER-ELEMENT ENDS.

1,112,868.

Specification of Letters Patent.

Patented Oct. 6, 1914.

Application filed June 18, 1914. Serial No. 845,789.

To all whom it may concern:

Be it known that I, PETER THOMSEN, a subject of the Emperor of Germany, residing at Cassel-Wilhelmshöhe, Germany, have invented a new and useful improvement in Connecting Members for Superheater-Element Ends, of which the following is a specification.

My invention relates to superheaters, and especially to superheaters of the flue tube class, in which a number of superheater pipes are inserted in some or all of the flue tubes and have their ends connected respectively to collecting chambers of a suitable header.

More particularly, my invention relates to a special type of connecting member by means of which two or more superheater elements may be combined together so as to constitute a unitary structure capable of being attached or detached as such from the header; by the use of my invention, furthermore, only one opening is required in each header chamber for connection with the plurality of tube ends belonging to each group of associated superheater elements.

The object of my invention is to provide a means by which a plurality of superheater elements may be grouped together so as to be attached to and detached from the header as a unit in a simple and convenient manner.

A further object of my invention is to lessen the number of openings which must be made in the header for connection with the superheater element ends, thereby increasing the strength of the header and lessening the labor involved in its manufacture.

A still further object of my invention is to lessen the number of bolts and other connecting means required for connecting the superheater elements to the header, thereby simplifying construction and lessening the cost of manufacture.

My improved connecting member is so constructed that it entails no constriction of the steam flow as the steam passes into the superheater elements and passes said elements into the header.

My invention will be better understood by referring to the accompanying drawings, in which—

Figure 1 represents a partial longitudinal section through the connecting member of

my invention as arranged for attachment to two superheater elements and for joining them to the header; Fig. 2 is a section taken along the line 2—2 of Fig. 1; Fig. 3 is a section taken along the line 3—3 of Fig. 1; Figs. 4 and 5 represent a modified form of my invention adapted to combine three superheater elements into one group, Fig. 4 representing a central vertical section and Fig. 5 a transverse section taken along the line 5—5 of Fig. 4; Figs. 6, 7 and 8 represent another but different form of my invention as arranged for combining three superheater elements into one group, Fig. 6 representing a longitudinal section; Fig. 7 a transverse section along the line 7—7 of Fig. 6, and Fig. 8 a vertical section along the line 8—8 of Fig. 6.

Referring to the form of my invention shown in Figs. 1—3, the iron connecting piece 1 may be made from a flat rectangular bar, 75 and is pierced centrally for attachment, by means of a bolt 2, to the header (not shown) having collector chambers 3, 4 for saturated and superheated steam respectively. A pair of holes, 5—5 and 6—6, are bored into the connecting piece from the lower side thereof so as to extend to the plane 7 a little below the upper side. The diameter of these holes is such as to just receive the corresponding ends 8—8 and 9—9 of a pair of superheater elements. These ends are only inserted for a short distance into the connecting piece, say to the plane 10 a little above the lower side and may be fastened in any preferred manner. Holes 11, 12, each centrally disposed as to the pairs of holes 5—5 and 6—6, are bored from the upper side of the connector piece down to the plane 10, to which the ends 8—8, 9—9 extend, and in each hole is fixed a short pipe connection 13 which extends into the connector piece to the plane 7, at which the holes 5—5 and 6—6 terminate, and projects above the top surface of the connector piece so as to fit into an enlargement of a bore 14 drilled through the bottom of the collector chambers 3 and 4. The area of the bore 14 should be about equal to the combined area of the pipe ends 8—8 and 9—9.

In the form shown in Figs. 4 and 5, the connector piece is a disk having three holes, 15, bored from the underside. Similar ends of three superheater elements 16 are fitted

into the three holes 15. Here one connector piece is used for the saturated steam ends and a separate connector piece for the superheated steam ends.

5 In the form shown in Figs. 6-8, also each set of ends of three superheater elements has its own connector piece. Bolt holes 17 for attachment to the steam collector are at opposite ends, instead of being in the center 10 as in Figs. 1-3. The three element ends, 16, enter centrally disposed holes 15' bored from the underside which holes connect with a single central hole bored in the upper side and adapted to register with a corresponding hole in the steam collector. In the specific construction here shown the hole which is bored from the top to receive the pipe connection 13 is enlarged somewhat 15 between the planes which bound the bottom 20 of pipe 13 and the tops of pipes 16, as shown in Fig. 7, as otherwise the two laterally disposed pipes 16 would have no outlet through to pipe 13. This enlargement should be sufficient to insure an opening between each 25 lateral pipe 16 and the central pipe 13 at least as great in section as the section of said pipe 16 so as not to restrict the flow of steam from pipe 16 to pipe 13. In the particular form here shown the area 18 represents the 30 amount by which the hole for pipe 13 has been enlarged between the planes referred to.

It will be noted that in my improved connector piece not only are the holes bored from opposite sides so as to communicate 35 with one another, but said oppositely bored holes extend in each case nearly to the side of the connector piece opposite to that from which they started. The pipe ends 8, 9, 16 and the tube sections 13, being extended only 40 for a short distance from the side at which they enter, there is, therefore, a lateral opening of the element end holes into the collector hole such that, the section of the collector hole being equal to the section of the 45 pipe holes as explained, there is no constriction of the steam flow anywhere between the superheater elements and the collector chambers.

Other modified forms of my invention 50 may be made within the spirit thereof.

It should be noted that the connecting

member of my invention may be made from solid material always to be found upon the open market and that the manufacturing operations necessary are of the simplest mechanical character as, *e. g.*, drilling, boring, reaming, etc. In some modifications turning, milling or planing operations may be helpful. While, as I have stated, I have intended my improved connecting member 55 more especially for connecting superheater elements to steam collectors or headers therefor, the same is, nevertheless, equally applicable to many other types and kinds of apparatus where fluids are to be carried as 60 for example, to feed water heaters, steam heating apparatus, steam generating and distributing apparatus generally, and the like and the scope of the claims which follow is to be taken as including such apparatus.

Having described my invention, I claim:—

1. A connecting member for joining a plurality of pipes to a single pipe, comprising a solid block having holes bored from 75 one side to receive the plurality of pipes, and a hole bored from the other side, intersecting each of the first named holes, to receive the single pipe the cross section of the bore for the single tube being substantially equal to the combined cross section of the plurality of pipes.

2. A connecting member for joining a plurality of pipes to a single pipe, comprising a solid block having holes bored 85 from one side to receive the plurality of pipes, and a hole bored from the other side, intersecting each of the first named holes, to receive the single pipe the cross section of the bore for the single tube being substantially equal to the combined cross section of the plurality of pipes, the smaller holes and the single larger hole being both extended 90 past the central plane of the block.

In testimony whereof, I have hereunto 95 set my hand in the presence of two subscribing witnesses.

PETER THOMSEN.
